(57) **CLAIM**

The ornamental design for a face rest, as shown and described.

DESCRIPTION

FIG. 1 is a perspective view of the face rest of my new design. FIG. 2 is another perspective view of the face rest of my new design showing it being attached to a beach type lounge chair. FIG. 3 is top plan view of the face rest shown in FIG. 1. The view from the bottom would be identical thereto.

FIG. 4 is an elevational view from the top edge of the face rest shown in FIG. 3; and,

An elevational view from the bottom edge would be identical to FIG. 4.

FIG. 5 is an elevational view from the left side of the face rest shown in FIG. 3.

An elevational view from the right side would be identical to that shown in FIG. 5.

The broken line chair shown in FIG. 2, is an environmental background element and forms no part of the invention.
